SKATING RINK

Frank S. Strite, New York, N. Y.

Application October 10, 1931, Serial No. 568,189

39 Claims.

(Cl. 62—12)

This invention relates to skating rinks, and more particularly to a skating rink which can be formed within a swimming pool, or the like.

An object of this invention is to provide means which may be readily inserted in any desired depression or tank whereby ice may be formed within the tank or reservoir, the ice being of any desired thickness, depending upon the use for the ice.

10 A further object of this invention is to provide an ice making apparatus which can be readily coupled up with the water circulating system for the swimming pool or tank, so that the tank may be used during the winter months or during 15 the cooler months for ice skating and used for swimming purposes during the warmer months.

A still further object of this invention is to provide a movable floor or ice supporting member which can be suitably adjusted within the tank 20 and maintained in such adjusted position during the time the tank is used for ice skating or during the time that the tank has the ice coated surface 25 therein.

Still another object of this invention is to provide an ice supporting member which is of relatively flexible or resilient construction, so that when the supporting member is lowered within the tank so that the tank can be used for swimming purposes, the supporting member will substantially conform to the configuration of the 30 tank floor or bottom.

The above and various other objects and advantages of this invention will in part be described in and in part be understood from the 35 following detailed description of the present preferred embodiment, the same being illustrated in the accompanying drawings, wherein:—

Figure 1 is a detail top plan view partly broken away of a device constructed according to the 40 preferred embodiment of this invention mounted in a tank or swimming pool;

Figure 2 is a longitudinal section partly broken away of the swimming tank, and

45 Figure 3 is an enlarged fragmentary sectional view showing the preferred manner of elevating the ice supporting floor or member and maintaining the floor in desired elevated position.

Referring to the drawings wherein like numerals of reference designate corresponding parts 50 throughout the several views, the numeral 10 designates generally a tank or reservoir used for swimming purposes, or for the purpose of receiving a relatively large quantity of water. This tank or reservoir 10 is provided with an inclined bottom 11 which has a drain outlet 13 to which is attached a pipe connection 12. This pipe connection 12 is connected to a drain pipe 14 and a pump or water pressure member 15 is interposed in this pipe 14, so as to draw the water 55 out of the drain 13 and pass this water through

the circulating pipe 16, which returns the water or liquid back to the tank or reservoir 10.

A conventional water filtering member F is interposed in the pipe connection 16, so as to filter this water as it is continuously circulated through the pipe 16 and back to the tank or swimming pool 10. A motor or power member M is connected to the pump 15. In order to convert the tank or reservoir 10 into a skating rink or to provide a frozen surface adjacent the upper edge 10 thereof, I have provided a relatively large plate or ice supporting member, generally designated as 17, which is constructed in the form of a sheet of metal of suitable thickness but having relative flexibility, the purpose for which will be hereinafter described. This ice supporting member 17 is elevated with respect to the bottom 11 of the reservoir 10 by means of a plurality of jacks J which engage the bottom 11 and are threadably engaged with the ice supporting floor or member 17. These jack members J are operable at will so that the ice supporting member 17 can be raised as may be desired, whether the member 17 has ice thereon or not. These jack members J have a square or angular head 18 by which 25 the screw members may be turned so as to raise or lower the ice supporting member 17 as desired.

A considerable number of these jack members J are used which are spacedly mounted in substantially vertical position on the floor 11 and are spaced apart sufficiently so that the ice supporting member 17 will be maintained in a substantially horizontal position. The vertical wall 19 of the tank 10 is provided adjacent the upper edge 30 thereof with a rim or water-tight edge member 20 which, in the present embodiment, is disclosed as being constructed in substantially oval or elliptical form. This rim or curb member 20 may be secured to the walls 19 of the tank 10 in any desired manner, and the curved portions 21 thereof across the corners of the tank may be secured in any desired manner to the ice supporting plate 17 so that when the curb 20 is in desired position, no water will seep downwardly into the space between 35 the ice supporting member 17 and the bottom 11 of the tank 10.

In order to freeze the water positioned on the ice supporting plate 17 within the curb 20, I have provided a plurality of spray members 22 which are connected to lateral pipe connections 23 which in turn are connected to longitudinally extending pipe members 24. These pipe members 24 are connected to a feed pipe 25 which in turn is connected with the pipe line 16 of the swimming pool 50 pipe system. A brine cooling member B is interposed in a pipe line 26 which is connected at each end to the pipe line 16 by means of short pipe connections 27, and valve members 28 and 29 are interposed in the pipe line 26 and are adapted to 55 60

control the passage of brine or other cooling medium through the cooling member B.

Valve members 30 and 31 are mounted in the pipe line 16, one on each side of the water filtering member F, so that when the circulating system for the pool is used for conducting the cooling medium to the spray members 22, the filtering member F may be cut out and the cooling medium passed through the liquid cooling member B, 10 using the pump or circulating member 15 for the cooling medium in the same manner as it is now being used for the pool circulating system. The ice supporting plate 17 is provided adjacent each corner thereof with trap doors T, so that access 15 may be had to the space between the supporting member 17 and the bottom 11 of the tank. A drain valve 32 is interposed in the pipe line 14 and is provided with an elongated stem 33 having a hand wheel 34 mounted thereon, so that when 20 the pool or tank is being used for swimming purposes, the water may be drained out of the tank and system to a suitable source of drainage.

In the use of this device, during the time that the tank 10 is being used as a swimming pool or 25 for holding liquids, or the like, the ice supporting floor 17 may be lowered so that it will contact with the floor 11 and the screws 35 forming a portion of the jack construction may be removed. Due to the flexibility of the floor 17, when this 30 floor is lowered so as to contact with the bottom 11, it will substantially conform to the configuration of the floor and the openings in the floor 17 caused by removing the screw members 35 will permit the water in the pool 10 to flow on the inclined 35 surface of the bottom 11 toward the drain opening 13. Preferably, the bottom 11 is provided with a plurality of base members 36 for the jacks J, so that the bottom 17 will not lie flat on the bottom 11, but will be held in spaced relation thereto so 40 as to permit the free circulation of water in the pool. During the use of the tank 10 as a pool, the valves 28 and 29 will be closed and the valves 30 and 31 opened so as to permit the water to circulate through the pipes 14 and 16 without passing 45 through the cooling member B.

When it is desired to use the tank 10 as a skating rink or the like, the jack members 35 may be inserted in desired position and the ice floor 17 raised to the desired height and the longitudinal 50 pipe connections 24 connected up to the brine header 25. A suitable brine or liquid is placed in the system, this liquid being such that when it is properly cooled in the brine cooling member B and sprayed through the spray nozzles 22, it will 55 cool the ice floor 17 sufficiently to freeze water on the upper surface of the floor 17 to any desired thickness.

After the liquid is ejected from the spray nozzles and drops downwardly from the lower 60 surface of the ice bottom member 17, it will drain into the outlet 13 and be drawn back into the system by means of the pump member 15. In this manner, a relatively small quantity of brine or freezing liquid may be used, the liquid being 65 used continuously and none of the liquid passing out of the system until the drain valve 32 is opened. While the floor 17 has been designed for the purpose of supporting ice within the tank 10, I do not wish to be limited to this particular construction as, if desired, other material may be placed on the floor 17 so that any desired games or sports events may be played on this elevated floor construction.

It will be obvious, from the foregoing, that 75 where a pool has been provided in the interior of

a building or the like, it will be possible to use the space occupied by the pool for purposes other than swimming, so that where the amount of space available is relatively limited, any desired sports such as swimming, ice skating, tennis or other sports events may be held by using the device hereinbefore described.

The use of the words "swimming pool" in the claims is to be construed as any tank or kindred structure having a drain in the bottom thereof.

It is, of course, understood that various changes and modifications may be made in the details of construction and design of the above specifically described embodiment of this invention without departing from the spirit thereof, such changes and modifications being restricted only by the scope of the following claims.

What is claimed is:—

1. A device of the character described comprising the combination with a swimming pool structure and a liquid circulating system for the swimming pool, of a removably mounted plate positioned within the pool structure, means for retaining a liquid on the plate, means for supporting the plate in upwardly spaced relation to the bottom of the pool, liquid cooling means interposed in the circulating system of the pool, and means disposed intermediate the plate and the bottom of the pool for projecting a cooling medium against the lower surface of the plate.

2. A device of the character described comprising the combination with a swimming pool structure including a liquid circulating system, of a plate disposed within the vertical walls of the pool, means for supporting the plate in a position above the bottom of the pool, said means including screw members engaging the bottom of the pool and the plate, liquid cooling means interposed in the circulating system, and means for projecting a cooling medium against the bottom of the plate whereby to freeze a liquid disposed on the upper surface thereof.

3. A device of the character described comprising the combination with a swimming pool structure and a liquid circulating system for the swimming pool, of a removably mounted plate disposed within the vertical walls of the pool, means for supporting the plate in an elevated position, means for retaining a liquid on the upper surface of the plate, a trap door carried by the plate whereby to permit entrance to the space between the plate and the bottom of the pool, and means for projecting a cooling medium against the bottom of the plate whereby to freeze the liquid positioned on the upper surface of the plate.

4. A device of the character described comprising a plate, means for retaining a liquid on the upper surface of the plate intermediate the marginal edges thereof, means for supporting the plate in an elevated position, said supporting means including a plurality of jack members having a portion thereof projecting through the plate whereby to permit vertical adjustment of the plate, and means engaging the bottom of the plate whereby to freeze the liquid positioned on the upper surface thereof.

5. A device as described comprising a horizontally disposed liquid holding member, a catch basin below the member having an area substantially equal to the area of the member, means for supporting the member in adjusted position relative to the basin, and means supported intermediate the member and the basin to project a cooling means against the bottom of the member.

- for freezing of a liquid positioned on top of the member, said catch basin receiving the cooling means dropping from the member.
6. A device as described comprising a horizontally disposed liquid holding member, a catch basin below the member having an area substantially equal to the area of the member, means supported intermediate the member and the basin to project a cooling means against the bottom of the member, said catch basin receiving the cooling means dropping from the member, and means for supporting the member in adjusted position relative to the projecting means.
7. A device as described comprising a liquid holding member, a catch basin disposed below the member, means disposed between the member and the basin for freezing a liquid carried by the member, and supporting means for supporting said member in adjusted position, said supporting means being operable from above the member and being removable through the member.
8. A device as described comprising a liquid holding member, a catch basin disposed below the member, means between the member and the catch basin for freezing a liquid carried by the member, and means operable from above the member and extensible therethrough for supporting the member in adjusted position relative to the freezing means.
9. A device as described comprising a liquid holding member, a catch basin disposed below the member, means disposed between the member and the basin for freezing a liquid carried by the member, and threaded supporting members rotatably carried by the basin and threadably engaging the member to support the member in adjusted position relative to the basin.
10. A device as described comprising a member adapted to hold a liquid, a catch basin disposed below the member, means disposed between the member and the basin for freezing a liquid carried by the member, and supporting means for supporting said member in adjusted position relative to the catch basin, said supporting means being operable from above the member.
11. A device as described comprising a member adapted to hold a liquid, a catch basin disposed below the member, means disposed between the member and the basin for freezing a liquid carried by the member, and supporting means for supporting said member in adjusted position relative to the catch basin and the freezing means, said supporting means being removable through the member.
12. A device as described comprising a plate, means for supporting the plate in an elevated position above a substantially horizontal surface, means for projecting a freezing means against the surface of the plate to freeze a liquid positioned thereon, said plate having an opening therethrough, and a closure for the opening to permit access through the plate to the space below the plate.
13. A device of the character described comprising a floor member adapted to hold a frozen liquid, means for supporting the floor member within a pool above the bottom of the pool, said supporting means including screw threaded members engaging the bottom for adjustably supporting the member relative to the pool.
14. A device of the character described comprising a horizontally disposed plate, screw threaded supporting means swivelly supported below the plate and threadably engaging the plate for supporting the plate in an elevated position.
- position, a liquid cooling system, and means engaging said cooling system for projecting a cooling medium against the bottom of said plate whereby to freeze a liquid disposed on the upper surface thereof.
15. A device of the character described comprising the combination with a tank structure and a liquid circulating system for the tank, of a plate supported above the bottom of the tank and adapted to hold a liquid thereon, liquid cooling means interposed in the circulating system, and means disposed intermediate the plate and the bottom of the tank for projecting a cooling medium against the lower surface of the plate.
16. A device of the character described comprising a plate adapted to hold a liquid on the upper surface thereof, a liquid collecting means below the plate, means operable from above the plate and engaging the collecting means for raising the plate, and means between the plate and the collecting means for freezing a liquid carried by the plate.
17. A device as described comprising a member adapted to hold a liquid, a catch basin below the member, means disposed between the member and the basin for freezing a liquid carried by the member, and means engaging the member and the catch basin for raising the member relative to the catch basin, said means being operable from above the member.
18. A device as described comprising a member adapted to hold a liquid, a catch basin below the member, means disposed between the member and the basin for freezing a liquid carried by the member, and means engaging the member and the basin for raising the member relative to the basin, said latter means being removable through the member.
19. A device as described comprising a plate, a catch basin below the plate, means for raising the plate relative to the catch basin, means for projecting a freezing means against the bottom of the plate, and means for obtaining access to the space below the plate.
20. A device as described comprising a plate adapted to hold a liquid, a catch basin below the plate, means engaging the plate and the catch basin for raising the plate relative to the basin, said means being removable through the plate, means for projecting a freezing means against the surface of the plate to freeze a liquid positioned thereon, said plate having an opening therethrough, and a closure for the opening to permit access through the plate to the space therebelow.
21. A device as described comprising a horizontally disposed plate, screw threaded elevating means swivelly supported below the plate and threadably engaging the plate for raising or lowering the plate, a liquid cooling system, and means connected to said cooling system for projecting a cooling medium against the bottom of the plate whereby to freeze a liquid disposed on the upper surface thereof.
22. A device as described comprising a member adapted to hold a liquid, a catch basin below the member, means disposed between the member and the basin for freezing a liquid carried by the member, and means engaging the member to elevate the member relative to the basin.
23. A device as described comprising a member adapted to hold a liquid, a catch basin below the member, means disposed between the member and the basin for freezing a liquid carried by the member, and means operable at will for elevating the member relative to the basin.

24. A device as described comprising a member adapted to hold a frozen liquid, and a supporting means for the member, said supporting means including screw threaded means engaging the member from below for supporting the member in an elevated position. 5
25. A device as described comprising a member adapted to hold a frozen liquid, and a supporting means for the member, said supporting means including members engaging the first member from below and removable through the first member. 10
26. A device of the character described comprising the combination with a swimming pool structure, of a removably mounted plate, means for retaining a liquid on the plate, means for supporting the plate above the bottom of the pool, and means intermediate the plate and the bottom of the pool for projecting a cooling medium against the lower surface of the plate. 15
27. A device as described comprising the combination with a swimming pool structure and a liquid circulating system for the pool, of a removably mounted plate, means for retaining a liquid on the plate, means for supporting the plate in upwardly spaced relation to the bottom of the pool, liquid cooling means interposed in the circulating system of the pool, and means disposed intermediate the plate and the bottom of the pool 20 for projecting a cooling medium against the lower surface of the plate. 30
28. A device as described comprising the combination with a swimming pool structure and a liquid circulating system for the pool, of a removably mounted plate adapted to substantially close the open top of the pool, means for retaining a liquid on the plate, means for supporting the plate above the bottom of the pool, liquid cooling means interposed in the circulating system of the pool, and means disposed intermediate the plate and the bottom of the pool 25 for projecting a cooling medium against the lower surface of the plate. 40
29. A device of the character described comprising the combination with a swimming pool structure, of a plate, screw threaded means for supporting the plate within the walls of the pool structure in adjusted position relative to the bottom of the pool, means for retaining a liquid on the upper surface of the plate, and means disposed between the plate and the bottom of the pool 35 for freezing a liquid carried by the upper surface of the plate. 50
30. A device of the character described comprising the combination with a swimming pool structure of a relatively large plate, means for retaining a liquid on the plate, means for supporting the plate above the bottom of the pool structure, and means intermediate the plate and the bottom of the pool and independent of the plate for projecting a cooling medium against the lower surface of the plate. 55
31. A means for converting the basin of a swimming pool structure to an ice skating rink comprising a member adapted to hold a frozen liquid and to be disposed at a point upwardly from the bottom of the basin, and means disposed below the member for freezing a liquid on the member, said means being disposed within the basin of the pool structure. 65
32. A means for converting the basin of a swimming pool structure to an ice skating rink comprising a member adapted to hold a frozen liquid, means for supporting the member in upwardly spaced relation to the bottom of the pool, and means independent of the member for freezing a liquid on the member, said latter means being disposed within the basin of the pool structure. 70
33. A means for converting the basin of a swimming pool structure to an ice skating rink comprising a member adapted to hold a frozen liquid, and means for supporting the member in 10 upwardly spaced relation to the bottom of the pool structure, and means independent of the member and of the supporting means therefor to freeze a liquid on the member, said latter means being disposed within the basin of the pool 15 structure. 15
34. The combination with the basin of a swimming pool structure, of a member adapted to hold a frozen liquid and to engage the pool structure in a manner whereby the member is disposed in 20 upwardly spaced relation to the bottom of the basin, and means disposed below the member for freezing a liquid on the member. 25
35. A converting means for the basin of a swimming pool for converting the pool structure to an ice skating rink comprising the combination with the basin of the pool structure, of a member adapted to hold a frozen liquid on one surface thereof, and means disposed below the member for freezing a liquid on the member, said 30 means being disposed within the basin of the pool structure. 35
36. A means for converting the basin of a swimming pool structure to an ice skating rink comprising a relatively flat member, means carried by one surface of the member for retaining a liquid thereon for freezing, means for supporting the member relative to the basin, and means below the member and independent thereof for freezing a liquid on the member, said latter means 40 being disposed within the basin of the pool structure. 40
37. A means for converting the basin of a swimming pool structure to an ice skating rink comprising a member adapted to hold a frozen liquid, means for supporting the member adjacent the top of the basin, and means supported between the bottom of the member and the basin of the pool for freezing a liquid on the member, said latter means being disposed within the basin 50 of the pool structure. 50
38. A means for converting the basin of a swimming pool structure to an ice skating rink comprising a member adapted to hold a frozen liquid and having an area to substantially enclose the top of the basin, means for supporting the member in operative position, and means independent of the member and supported therebelow for freezing a liquid on the member, said latter means being disposed within the basin 60 of the pool structure. 60
39. The combination with the basin of a swimming pool structure, of a member engaging the basin and adapted to hold a frozen liquid and having an area substantially equal to the area 65 of the basin engaged by the member, means for supporting the member relative to the basin, and means independent of the member and supported therebelow for freezing a liquid on the member, said latter means being disposed within the 70 basin of the pool structure. 70
